UNITED STATES PATENT OFFICE.

JOHN W. BREWSTER, OF UNION CROSS-ROADS, TENNESSEE.

ALARM-CLOCK.

SPECIFICATION forming part of Letters Patent No. 588,550, dated August 24, 1897.

Application filed January 9, 1897. Serial No. 618,587. (No model.)

To all whom it may concern:

Be it known that I, JOHN W. BREWSTER, a citizen of the United States, residing at Union Cross-Roads, in the county of Roane and State 5 of Tennessee, have invented certain new and useful Improvements in Alarm Mechanism for Clocks; and I do hereby declare the following to be a full, clear, and exact description of the invention, such as will enable others skilled 10 in the art to which it appertains to make and use the same.

This invention relates to alarm mechanism for clocks, and has for its object to provide a simple and efficient device in the form of an 15 attachment applicable either to spring-actuated or weight-actuated clocks for the purpose of indicating by an audible alarm that the clock is about to run down and that the same needs rewinding.

20 To this end the invention consists in certain novel features and details of construction and arrangement of parts, as hereinafter fully described, illustrated in the drawings, and incorporated in the claims.

25 In the accompanying drawings, Figure 1 is a perspective view of the improved attachment. Fig. 2 is a view in elevation, showing the same applied to a weight-actuated clock and illustrating the manner in which the 30 alarm mechanism is actuated by the descending weight.

Similar numerals of reference designate corresponding parts in both figures of the drawings.

35 The improved attachment comprises a base-piece 1, which may be either of wood or metal, and upwardly-extending bearing-pieces 2, secured thereto and arranged at a suitable distance apart. Interposed between the bearing-pieces 2 is a bell or gong 3 of any desired form, the same being secured to the base 1. Upon one of the bearing-pieces 2 is fulcrumed the hammer 4. This hammer is carried by an arm 5, which is connected at one end to a 45 rock-shaft 6, having a spiral spring 7 disposed around the same and connected at one terminal to said rock-shaft, while the other terminal bears against the bearing-piece 2, the tension of said spring being exerted to throw 50 the hammer against the bell after said hammer has been raised and released. The rock-shaft is journaled in ears 7^a on the bearing-

piece 2 and is also provided with an arm 8, which extends toward and partially over the bell or gong 3.

55 Journaled upon the remaining bearing-piece 2 is a second rock-shaft 9, mounted in spaced ears 10, projecting from the upper side of said bearing-piece.

11 designates a lever which is secured intermediate its ends to the rock-shaft 9. One arm of this rock-shaft extends over the bell and has its extremity bent at an angle to the main body of the lever and provided at its end with a triangularly-shaped catch-lip 12, 60 which is adapted to engage with the arm 8 of the hammer for lifting the same. The opposite end of the lever 11 is adapted to be arranged under the descending weight of the clock, so as to be depressed by the same, thereby lifting the opposite end of the lever and operating the hammer. A spiral spring 13 is disposed around the rock-shaft 9, having one terminal in engagement therewith and the other terminal resting against the bearing- 70 piece 2, the tension of said spring being exerted to lift the outer end of the lever 11 and depress the opposite end thereof, so as to cause the same to engage with the arm 8 of the hammer.

80 The attachment hereinabove described is placed in the bottom of a clock-case, so that the outer end of the lever 11 will lie in the path of the descending weight.

As the weight moves downward and just 85 before the clock runs down said weight rocks the lever 11, thereby lifting that end which carries the lip and causing the same to engage the arm 8, thus elevating the bell-hammer. After the lever 11 has been rocked a sufficient 90 distance the extremity of the arm 8 passes off the catch-lip of the lever and the spring on the rock-shaft of the hammer, so as to throw said hammer quickly against the bell or gong, thus notifying a person in the room 95 that the clock is about to run down and that the same needs rewinding.

While the improved attachment has been shown and described as applied to a weight-actuated clock, it will be apparent that the 100 same may also be used in connection with spring-clocks by actuating the lever with any suitable part of the clockworks.

The attachment is very simple in construc-

tion and reliable in operation and may be readily applied to any clock already in use.

Having thus described the invention, what is claimed as new is--

- 5 1. An attachment for clocks, comprising a suitable base or frame, a bell mounted thereon, a rock-shaft, an arm extending therefrom and carrying the bell-hammer, a second arm connected to said rock-shaft for operating it, a spring for giving the bell-hammer a normal tendency, and a spring-actuated lever fulcrumed intermediate its ends and provided at one end with a catch-lip engaging the operating-arm of the bell-hammer, the opposite 10 end of said lever being adapted for engagement with the clock mechanism, substantially as described.
- 15 2. An attachment for clocks comprising a suitable base or frame, a bell mounted there-

on, a rock-shaft, an arm projecting therefrom and carrying a bell-hammer, a second arm for operating said rock-shaft, a second rock-shaft, a lever secured intermediate its ends thereto and provided at one end with a lip for engaging the operating-arm of the bell-hammer and 25 having its opposite end extended to be engaged by the clock mechanism, and a spring engaging said second rock-shaft for returning the lever to its normal position, substantially as described.

In testimony whereof I have signed this specification in the presence of two subscribing witnesses.

JOHN W. BREWSTER.
